UNITED STATES PATENT OFFICE.

LOUIS NICOLE, OF LONDON, ENGLAND.

MILLING, DRILLING, AND GRINDING APPLIANCE FOR LATHES.

Application filed April 2, 1921. Serial No. 458,098.

To all whom it may concern:

- Be it known that I, LOUIS NICOLE, a subject of the King of Great Britain and Ireland, residing at 17 Priory Road, West 5 Hampstead, London, England, have invented Improvements in and Relating to Milling, Drilling, and Grinding Appliances for Lathes, of which the following is a specification.
- 10 This invention relates to a new or improved appliance for lathes whereby milling, drilling, grinding and like operations may be readily and efficiently executed on lathes.
- 15 The object of the present invention is to produce an inexpensive appliance which can be readily fixed to the slide rest of a lathe and thus materially enhance the capabilities of such a machine for the production of a 20 wide and varied range of work, and is particularly useful for small shops and amateurs requirements.
- 25 The present invention comprises essentially a vertical stem carried by a base plate 30 adapted to be clamped or bolted to the slide rest or saddle of a lathe, a sleeve adjustably mounted to slide and be fixed on said vertical stem, a hollow spindle having its one end formed with a hollow taper to engage 35 "Morse" tapered arbours for carrying grinding wheels, milling cutters, drills or the like on its one end and with means for rotating it on its other end, a sleeve provided with 40 bearings—preferably ball bearings—within 45 which the said spindle is free to rotate and having means whereby it can be adjustably attached to the sleeve on the stem either 50 parallel or horizontally with respect to said stem or at any angle thereto and with or 55 without a slotted arm adjustably attached at right angles to said spindle bearing sleeve and carrying a stud adjustably mounted within said slotted arm and on which is 60 mounted a freely revolving toothed pinion 65 made in one with or carrying a pulley adapted to be driven from the over head motion of the lathe or by other means, the said 70 pinion meshing with a toothed wheel fixed 75 on the hollow spindle.
- 75 In the accompanying drawing which illustrates this invention:

Fig. 1 is a view in front elevation of a milling, drilling and grinding appliance embodying the present invention.

55 Fig. 2 is an end view thereof, partly in section.

Fig. 3 is a view in back elevation of the appliance with an attachment for gearing down the speed of the rotating tool.

Fig. 4 is a broken view in front elevation 60 of the appliance showing the spindle for the tool adjusted to a vertical position and with gearing and driving attachments and

Fig. 5 is a view in plan thereof.

Throughout the views similar parts are 65 marked with like letters of reference.

On a base plate *a* adapted to be clamped or bolted to the slide rest or saddle of a lathe is fixed a vertical stem *b*. On this stem *b* is so mounted a sleeve *c* as to be 70 capable of sliding and rotating thereon and to be fixed in any position it can be caused to assume. A convenient arrangement is to form the upper portion of the stem *b* with a screw thread *b*¹ with which a milled nut *b*² 75 engages. This nut *b*² is free to rotate on an inner sleeve *c*¹ but not to move up or down on the stem without imparting the same movement to the sleeve. The sleeve *c*¹ is prevented from rotating on the stem *b* by 80 forming it with keys *c*² engaging a groove or keyway *b*^{*} formed on the stem. The outer side of the sleeve *c*¹ is embraced by the sleeve *c* which is split and furnished with a screw *c*³ so as to enable the sleeve *c* to be 85 adjusted angularly and locked to the sleeve *c*¹. The sleeve *c* is prevented from moving axially with respect to the sleeve *c*¹ by reason of a flange on its upper edge engaging the under side or a flange thereon of the nut *b*² and its lower edge engaging a collar *c*⁴ 90 locked to the sleeve *c*¹. The sleeve *c* is formed in one with or carries a disc *c*⁵ to which is fixed a stud *c*⁶. On this stud *c*⁶ is mounted a disc *d* which frictionally 95 engages the outer surface of the disc *c*⁵ and can be locked thereto in any required position by a nut *c*⁷ threaded on the free end of the stud *c*⁶. The disc *d* is formed in one with a sleeve *d*¹ which is provided with bearings—preferably ball bearings—for the reception of a spindle *e*. This sleeve *d*¹ is shown with plain bearings on the drawing in which case it may split and provided with screws as shown for drawing it together to 105 compensate for wear.

The spindle *e* is preferably a hollow one having its one end formed with a hollow taper to engage "Morse" tapered arbours for carrying grinding wheels, milling cutters, 110 drills or the like on its one end and with a pulley *e*¹ on its other end for rotating it.

For milling or other operations requiring a lower speed the spindle *e* instead of being directly driven, is driven by means of change wheels, in which case, (see Fig. 3) a slotted 5 arm *f* is adjustably attached at right angles to one end of the bearing sleeve *d*¹ and is provided with a stud *g* adjustably mounted within the slotted or free end part of the arm. On this stud *g* is mounted a freely revolving toothed pinion *x* made in one with or carrying a driving pulley *g*¹ adapted to be driven from the overhead motion of the lathe or by other means, the said pinion *x* meshes with a toothed wheel *x*¹ fixed on the 10 spindle *e*. In some cases where the spindle is arranged parallel with the stem *b*¹ (see Figs. 4 and 5) or at an angle thereto it may be necessary to interpose guide pulleys *y* for the driving belt or cord *z* which can be 15 conveniently arranged by bolting an auxiliary arm *h* to the slotted arm *f*, which arm *h* carries the bearing spindle for the said pulleys.

In some cases the milling cutter or other 20 tool may be carried between the centres of the lathes or by a headstock in which case the work to be operated upon is mounted on the spindle and a division plate is mounted on the opposite end of the spindle, this arrangement is shown in dot and dash lines 25 on Figs. 1 and 2 where *x*² indicates a toothed gear wheel used as a dividing head and a spring index finger or stop *i* is then carried by the stud *g* in the slotted arm *f*.

The periphery of either one of the discs 30 *c*⁵ or *d* may be graduated in degrees to register with a zero mark on one of said discs to furnish a ready means for setting the parts to any desired angle with relation to one 35 another. In use the appliance is bolted in position on the slide rest or saddle of the lathe and for high speed drilling, grinding, or like operations, the work to be operated upon is mounted between the lathe centres 40 or held by a chuck or the like in a headstock, the drill, grinding wheel, or other tool is mounted within a chuck or on an appropriate arbour carried by the hollow spindle *e* and the sleeve *d*¹ carrying it, is 45 adjusted to the desired angular position with respect to the sleeve *c* on the vertical stem *b* and the spindle *e* is driven directly, i. e. without the intervention of gearing from the over head motion of the lathe or by 50 other means, by a bolt or cord passing over the pulley *e*¹, for milling or other operations requiring a lower speed the spindle *e* is driven by means of change wheels, see Figs. 3, 4 and 5 and if the milling cutter 55 or other tool is carried between the centres of the lathe or by a headstock and the work to be operated upon is mounted on the spindle *e* (see Figs. 1 and 2) the toothed gear wheel *x*² is mounted on the opposite end of 60 said spindle to act as a dividing head in con-

junction with spring index finger or stop *i* carried by the stud *g* in the slotted arm *f*.

I claim:

1. A milling, drilling and grinding appliance for lathes comprising a vertical stem 70 carried by a base plate adapted to be clamped to the slide rest of a lathe, a sleeve mounted so as to be angularly adjustable on said stem and slidable thereon, a spindle adapted to carry at its one end a rotating 75 tool and having at its other end means for rotating it, a sleeve provided with bearings in which the spindle is free to rotate and adjustably attached to the sleeve on the stem, a slotted arm carried by and at 80 right angles to the spindle bearing sleeve, a stud mounted adjustably on said slotted arm, and an index finger carried on said stud and adapted to engage a division plate on the spindle. 85

2. A milling, drilling and grinding appliance for lathes comprising a vertical stem carried by a base plate adapted to be clamped to the slide rest of a lathe, a sleeve mounted so as to be angularly adjustable on 90 said stem and slidable thereon, a spindle adapted to carry at its one end a rotating tool, a sleeve provided with bearings in which the spindle is free to rotate and adjustably attached to the sleeve on the stem, 95 a slotted arm carried by and at right angles to the spindle bearing sleeve, a stud adjustably mounted on said slotted arm, a freely revolving toothed pinion mounted in said stud, a toothed wheel fixed on said spindle and gearing with the toothed pinion on the stud and means for driving the toothed pinion. 100

3. A milling, drilling and grinding appliance for lathes comprising a vertical stem 105 carried by a base plate adapted to be clamped to the slide rest of a lathe, a sleeve mounted so as to be angularly adjustable on said stem and slidable thereon, a spindle adapted to carry at its one end a rotating tool, a sleeve provided with bearings in which the spindle is free to rotate and adjustably attached to the sleeve on the stem, a slotted arm carried by and at right angles to the spindle bearing sleeve a stud adjustably mounted on said slotted arm, a belt 110 driven toothed pinion mounted on said stud, a toothed wheel fixed on said spindle and gearing with the toothed pinion on the stud, an auxiliary arm bolted to the slotted arm, 115 a spindle carried by said auxiliary arm and guide pulleys for the belt driven toothed pinion mounted on said spindle. 120

4. A milling, drilling and grinding appliance for lathes comprising a vertical stem 125 carried by a base plate adapted to be clamped to the slide rest of a lathe, an inner sleeve mounted so as to be splined to said stem, an outer sleeve angularly adjustable on said inner sleeve, means for con- 130

necting the two sleeves together so that a sliding motion imparted to the inner sleeve is shared by the outer sleeve, screw and nut mechanism for sliding the sleeve on the 5 stem, a spindle adapted to carry at its one end a rotating tool and having a driving pulley fixed on its other end, a sleeve provided with bearings in which the spindle is free to rotate, a stud carried by the outer

sleeve on the stem, a bearing formed in one 10 with the spindle bearing sleeve and pivoting on said stud and means for fixing together the outer sleeve and bearing sleeve.

LOUIS NICOLE.
